(57) **CLAIM**

The ornamental design for a right angle attachment, as shown and described.

DESCRIPTION

FIG. 1 is a perspective view of the right angle attachment.

FIG. 2 is a front view thereof.

FIG. 3 is a back view thereof.

FIG. 4 is a left view thereof.

FIG. 5 is a right view thereof.

FIG. 6 is a top view thereof; and,

FIG. 7 is a bottom view thereof.

The portion in broken lines does not form any part of the claimed design.

1 Claim, 6 Drawing Sheets(56)
